By Geiger & Papp Attorneys.

UNITED STATES PATENT OFFICE.

JOSEPH VINCENT RIEFFEL, OF BUFFALO, NEW YORK.

SHEET-FOLDING DEVICE.

SPECIFICATION forming part of Letters Patent No. 747,085, dated December 15, 1903.

Application filed June 27, 1903. Serial No. 163,360. (No model.)

To all whom it may concern:

Be it known that I, JOSEPH VINCENT RIEFFEL, a citizen of the United States, residing at Buffalo, in the county of Erie and State of New York, have invented new and useful Improvements in Sheet-Folding Devices, of which the following is a specification.

This invention relates to a sheet-folding device which is more particularly designed for folding bills, letters, circulars, &c., but which may also be used for folding other articles of this kind.

My object is to produce a sheet-folding device for this purpose which is simple and durable in construction, which permits of rapidly and conveniently folding bills, &c., of uniform size, and which can also be used as an arm-rest for bookkeepers.

In the accompanying drawings, Figure 1 is a perspective view of my improved sheet-folding device. Fig. 2 is a fragmentary top plan view thereof, partly in section. Fig. 3 is a similar view of the tablet and the nut of the clamping-screw forming parts of the folding device. Fig. 4 is a vertical section in line 4-4, Fig. 2.

Similar letters of reference indicate corresponding parts throughout the several views.

A represents the base or tablet of my improved sheet-folding device, which is preferably of rectangular form and constructed of wood; but the same may be of any other suitable form and material. On top of the tablet is arranged an L-shaped gage-bar, having its members B C constructed to form front and side gages or gage-faces b c on their inner sides. These gages are arranged at right angles to each other and are adapted to be engaged by the front and side of the sheet for squaring the same preparatory to folding it. The side gage member C is preferably arranged transversely near one end of the tablet, and the front gage member extends longitudinally inward from one end of the side member C. The gage-bar may be secured to the tablet in any suitable manner—for instance, by means of screws d, as shown.

E represents a folding bar or blade around which the sheet is folded after being squared against the gages. This bar is arranged lengthwise of the tablet and extends at its outer end over the side gage-bar, while its

inner end extends over the tablet, but is separated therefrom by an intervening space e, which receives the sheet preparatory to squaring and folding the same. The outer longitudinal edge or face f of the folding-bar is parallel with the front gage-face, so that upon folding the lower end of the sheet over this bar the same will register with the upper part 60 of the sheet.

When it is desired to fold a sheet, the front end thereof is slipped between the tablet and the folding-bar, and after its front and outer side edges have been squared against the front and side gages the lower end of the sheet is doubled or folded over the folding-bar and creased along the folding edge f of the folding-bar, after which the sheet in its folded or creased condition is withdrawn from between the tablet and folding-bar. If required, several parallel folds or folds at right angles to each other may be produced in the sheet by means of this folding device.

In order to permit of varying the extent of the fold which is produced in the sheets, means are provided for adjusting the folding-bar toward and from the front gage without disturbing the parallel relation of the folding edge and front gage-face. Various means may be employed for this purpose. I prefer those shown in the drawings, which are constructed as follows:

Formed lengthwise in the side gage member and at right angles to the front gage member is a slot G, and below this slot the top of the tablet is provided with a groove g, which extends lengthwise in the same direction as the slot and is somewhat wider than the slot, so that longitudinal shoulders are formed on the under side of the side gage-bar on opposite sides of its slot.

H represents a clamping screw-bolt, which extends vertically through the outer end of the folding-bar and the slot in the side gage-bar. The head of this bolt bears against the top of the folding-bar, while its nut h is arranged in the groove g of the tablet and bears against the under side of the side gage-bar on opposite sides of its slot. Upon loosening the bolt the folding-bar may be adjusted toward and from the front gage for varying the width of the fold in the sheets. For the purpose of enabling the folding-bar to be readily

set or adjusted to the required position for producing a predetermined width of fold in the sheets the side gage-bar is provided with a scale or graduations *i*, relatively to any one 5 of which the folding edge of the bar *G* may be brought into alinement. The nut of the clamping-bolt is preferably square and engages its opposite flat sides with the longitudinal sides of the groove in the tablet, there-
10 by holding the nut against turning with the bolt, but permitting the same to move trans- versely therewith upon shifting the location of the folding-bar.

For preventing the folding-bar from becoming displaced and compelling the same to always remain with its folding edge in parallelism with the front gage-face a tongue or rib *J* projects from the under side of the folding-bar into the slot of the side gage-bar and is 15 provided with opposite flat faces, which engage with the corresponding flat or straight longitudinal sides of the slot, thereby permitting the folding-bar when loose to be freely adjusted toward and from the front gage-
20 face, but preventing the folding-bar from turning in a plane parallel with the face of the tablet.

It has been found in practice that the folding-bar need not be so long as the front gage, 30 but may be made comparatively short, because the crease when properly started at one end of the sheet adjacent to the folding-bar can be completed without the presence of the folding-bar.

35 My improved sheet-folding device permits of folding the various papers which are commonly used in office-work uniformly and expeditiously, thereby enabling such papers to be put up in neat packages and permitting 40 the same to be handled more readily than papers which have been folded irregularly.

In addition to serving as a sheet-folding device the same can be used as an arm-rest adjacent to a book into which entries are being 45 made. For this purpose the inner end of the tablet extends some distance beyond the inner ends of the front gage-bar and the folding-bar, so as to permit this end of the tablet to be inserted between the leaves of a book, 50 leaving the outer end projecting for supporting the arm of the writer.

I claim as my invention—

1. A sheet-folding device comprising a tab-

let, a front gage and a side gage arranged on the tablet at right angles to each other, and a 55 folding-bar arranged slightly above the surface of the tablet and parallel with the front gage and supported at its outer end at the side gage while its inner end is unsupported forming an unobstructed space between this 60 end of the bar and the tablet, substantially as set forth.

2. A sheet-folding device comprising a tablet, a front gage and a side gage arranged on the tablet at right angles to each other, a fold- 65 ing-bar arranged slightly above the surface of the tablet and parallel with the front gage and having its inner end unsupported forming an unobstructed space between this 70 end of the bar and the tablet, and adjusting means supporting the bar at the side gage and permitting the bar to be moved toward and from the front gage, substantially as set forth.

3. A sheet-folding device comprising a tablet, a front gage and a side gage secured to 75 the tablet at right angles to each other, a fold- ing-bar having its inner end unsupported forming an unobstructed space between this 80 end of the bar and the tablet, and means ad- justably connecting the outer end of the fold- 85 ing-bar and the side gage and retaining the same parallel with the front gage, substan- tially as set forth.

4. A sheet-folding device comprising a tab- 90 let having a groove in its top, an L-shaped 85 gage-bar secured to the top of the tablet and having a front and side member arranged at right angles to each other, said side member being arranged lengthwise over said groove and having a longitudinal slot, a folding-bar 95 arranged parallel with the front gage mem- ber and separated at its inner end by an in- tervening space from the top of the tablet while its outer end is provided with a tongue which projects downwardly into the groove 95 in the side gage member, and a clamping- bolt passing through the folding-bar and hav- ing its nut arranged in said groove and bear- ing against the under side of the side gage member, substantially as set forth. 100

Witness my hand this 24th day of June, 1903.

JOSEPH VINCENT RIEFFEL.
